UNITED STATES PATENT OFFICE.

PHELPS JOHNSON, OF MONTREAL, CANADA.

COLUMN.

SPECIFICATION forming part of Letters Patent No. 573,151, dated December 15, 1896.

Application filed January 21, 1896. Serial No. 576,355. (No model.)

To all whom it may concern:

Be it known that I, PHELPS JOHNSON, of the city of Montreal, in the district of Montreal and Province of Quebec, Canada, have 5 invented certain new and useful Improvements in Columns; and I do hereby declare that the following is a full, clear, and exact description of the same.

My invention relates more particularly to 10 metal columns for supporting "trolley-wires" or the wires of telephone, telegraph, electric lights, electric power, or other like systems, although it is equally applicable wherever tapered columns are required.

15 The object of the invention is to provide columns for the purposes indicated, built up of cheap and easily-obtained sections of rolled metal at small expense for labor and manufacture, that will readily permit the attachment 20 of cross-arms, brackets, and other connections for wires, that will be pleasing in appearance, and so proportioned and shaped that the strength or resistance of the column against bending will increase from top to bottom or to the point of support against horizontal stresses, (usually at the ground-level,) as it is desirable to resist the strains caused 25 by wind stresses, unbalanced stresses from the wires supported, and other horizontal 30 stresses to which the column may be subjected at or near the top.

The desired results of pleasing appearance and varying strength of the column can best be obtained by making the columns tapered, 35 increasing in both or all lateral dimensions from the top toward the bottom, and of such construction that the area of metal available for resisting bending strains increases from the top toward the bottom of the column.

40 My invention may be said, briefly, to consist in combining into the form of a tapered column four angles having one or both legs tapered or of varying width and a tapered web, which may be a plate-web, throughout 45 the length of the column, or a lattice-web throughout the length of the column, or any combination of plate and lattice webs or cross-bars and tie-plates, so long as the four tapered angles are firmly united by the web 50 member or members and are kept in proper position, the smaller ends of the tapered angles being always at the top of the column

and the uneven legs of the angles being placed perpendicular to the web of the column. The tapered angles may be made either by bending tapered plates into angular form or by shearing off a portion of the legs of ordinary rolled angles, or in any other way; but it is my preference to obtain the tapered angles by cutting ordinary rolled channels longitudinally and slightly diagonally along the web, each channel thus making two angles, having one leg of varying width and two channels cutting without waste into the four angles required for a column, and the construction 60 described readily admits of the attachment of cross-arms, brackets, side pins, and all other necessary supports for insulators and wires.

For full comprehension, however, of the 70 invention reference must be had to the accompanying drawings, forming a part of this specification, in which like symbols indicate the same parts, and wherein—

Figure 1 represents in plan view a section 75 of channel-iron divided according to my invention. Fig. 2 is a side elevation of a complete column constructed according to my invention. Fig. 3 is a longitudinal sectional view thereof, taken on line 3 3, Fig. 2. Fig. 80 4 is a transverse horizontal sectional view taken on line 4 4, Fig. 2. Fig. 5 is a similar view to Fig. 4, but taken on line 5 5, Fig. 2; Fig. 6, a similar view to Figs. 4 and 5, but taken on line 6 6, Fig. 1; Fig. 7, a view similar to Fig. 4, but enlarged and illustrating the application of reinforcing-sections thereto.

I prefer to construct a column by dividing an ordinary section of channel-iron 7 diagonally, as shown by line 10 in Fig. 1, thus 90 forming tapered lengths of angle-irons 8 and 9. These lengths of angle-iron are then connected together at their wider ends, preferably by a solid tapered web-section 11, extending about one-third of the length thereof, 95 and to the edges of which the flanges 8^a and 9^a of the lengths 8 and 9 are riveted. The balance of the length of these angle-irons may be connected together at intervals either by transverse bars 13, or, as I prefer, by lattice-work formed of diagonal bars 12, connected 100 at their ends between the flanges 8^a 9^a of the lengths of angle-iron. When a column thus formed is to be used for supporting trolley-

wires, the transverse bars 13 would preferably be extended at one end to project laterally in the direction of such trolley-wire and perforated, as at 13^a, to allow the usual 5 hanger-wires 14 to be connected therewith, or a bracket-piece could be riveted to the side of the column.

In a case where cross-arms would be required, as in telephone or telegraph poles, 10 any preferable form of cross-arm may be secured near the upper end of the column and suitably braced, either as shown in dotted lines in Fig. 2 or otherwise.

For columns of unusual height or requiring 15 to be of unusual strength the construction described above may be readily reinforced either by riveting to the outside of the adjacent angle-irons 8 and 9 tapered reinforcing-plates 17, of such length as may be 20 necessary, or by riveting to the inside of the legs of such angle-iron rolled bars 18 or angle-irons 19, or be reinforced in any other desirable way.

It is not essential that the column be 25 tapered full length, and it will sometimes be economical and not unsightly to make the portion in the ground and just above the ground surface of uniform width in one or both dimensions; but for strength and for 30 appearance it is essential that the columns be tapered for the greater portion of visible length.

It will be obvious that any of the modifications mentioned and illustrated of the means 35 for supporting wires may be used and other changes in the construction made, such as making the column of one even width throughout, and the invention adapted to various uses other than for supporting telephone, telegraph, and trolley wires without departing 40 from the spirit of my invention.

What I claim is as follows:

1. A metallic column tapering on all sides and composed of a tapered central web-section, and four tapered lengths of angle-iron 45 disposed to form four outside corner-sections of a quadrangular structure and each corner-section having two side portions, one of which is of the same width throughout its entire length and secured to the web-section and 50 the other of tapering width and projecting at right angles to the web-section, for the purpose set forth.

2. A metallic column tapering on all sides and composed of a tapered central web-section, and four tapered lengths of angle-iron 55 disposed to form four outside corner-sections, of a quadrangular structure and each corner-section having two side portions one of which is of the same width throughout its entire 60 length and secured to the web-section and the other of tapering width and projecting at right angles to the web-section, with single reinforcing-plates extending over the outside surfaces of the tapered side portions of two 65 adjacent corner-sections and secured to such sections, for the purpose set forth.

3. A metallic column tapering on all sides and composed of a tapered central web-section, and four tapered lengths of angle-iron 70 disposed to form four outside corner-sections of a quadrangular structure and each corner-section having two side portions, one of which is of the same width throughout its entire length and secured to the web-section and 75 the other of tapered width and projecting at right angles to the web-section with one or more cross-arms secured rigidly between said length of angle-iron and projecting laterally of the column, for the purpose set forth.

PHELPS JOHNSON.
